LIQUID DISPENSING APPARATUS COMPUTING REGISTERING MECHANISM

Einar M. Orbeck, Muskegon, Mich., assignor to John Wood Manufacturing Company, Inc., Conshohocken, Pa., a corporation of Delaware

Original application May 27, 1937, Serial No. 145,056. Divided and this application September 18, 1937, Serial No. 164,542

3 Claims. (Cl. 74—349)

This mechanism was designed for inclusion in liquid dispensing apparatus computing registering mechanism of the character disclosed in Letters Patent of the United States No. 2,062,997 granted to me December 1, 1936.

Such computing registering mechanism includes means for indicating any selected price basis of the computation, means for indicating the volume of liquid dispensed at each operation, 10 in gallons and fractions of a gallon; means for computing and registering the value of the volume dispensed at each dispensing operation in cents and fractions of a cent; and means for indicating such value. That mechanism includes 15 a driving element, to wit, a shaft, which is rotated by and in accordance with the operation of a meter by the passage through the latter of the liquid to be dispensed and the change speed mechanism herein claimed connects that driving element with a driven element which actuates the computing registering mechanism indicators, and is adapted to be manually changed in accordance with each change in the price basis of the computation, to wit, the price per 20 gallon of the liquid dispensed. An essential feature of the mechanism herein claimed is a detent lever which is spring pressed to engage a detent gear element of the speed change mechanism and prevent the operation of said mechanism unless and until said mechanism is properly set in accordance with a selected price.

My invention includes the various novel features of construction, arrangement and method of operation hereinafter more definitely specified. 35 In said drawings: Fig. I is a plan view of a change speed mechanism embodying my invention in the relation essential to their cooperation in such computing registering mechanism.

Fig. II is an elevation of the mechanism shown 40 in Fig. I, as seen from the lower side of the latter.

Fig. III is a vertical sectional view of said mechanism taken on the line III, III in Fig. I, in the direction of the arrows on that line, but 45 omitting various parts of the computing registering mechanism.

Fig. IV is an elevation of the interlocking mechanism between the fractional cent price indicating dial and the computing registering 50 mechanism, and including said spring pressed detent lever.

Referring to Figs. I and II, the driving element is the shaft 3. The detent gear 72 is operatively connected with two conical assemblages of gears 55 36 and 37 with their axes parallel, the gears in

each assemblage being in coaxial relation. The selector gear 34 is adjustable axially, parallel with the axes of said gear assemblages 36 and 37, and transversely thereto for selective connection with any two opposite gears in said two 5 assemblages. The locking means for said change speed mechanism, includes the spring pressed detent lever 32' for engaging teeth of said detent gear 72, and thereby rendering said change speed mechanism inoperative unless and until 10 said selector gear 34 is properly engaged with any selected gears of said assemblages 36 and 37. Means for releasing said detent lever 32' from engagement with the teeth of said detent gear 72, consequent upon proper engagement of said 15 selector gear 34 with said assemblages 36 and 37, includes the shaft 32, which supports said selector gear 34, and has a flattened eccentric portion and a concentric cylindrical portion, as indicated in Figs. II and IV, which are alternately presentable in registry with said detent lever 32' by rotation of said shaft 32; said detent lever 32' being engaged with said detent gear 72 by its spring 32'', when the eccentric portion of said shaft 32 is presented to said lever 20 32'. Said detent lever 32' is displaced from engagement with said detent gear 72 when the cylindrical portion of said shaft 32 is presented to said detent lever 32'. Means for manually turning said shaft 32, include the blade 31', 25 forming a handle, having the projection 31'' extending in the keyway 32a of said shaft. The rocker frame 33 which holds said blade 31', in its slot 33', is axially movable on said shaft 32 with said selector gear 34.

As shown in Fig. III, the cylinder 29 is rigidly connected with the price indicating dial 21 by which it may be manually turned, and includes a plurality of slots 30 in its circumference spaced both circumferentially and axially in accordance 40 with respective prices indicated on said dial. That construction and arrangement are such that in order to set the change speed mechanism for a selected price, the operator must turn the blade 31' clockwise from the position shown in 45 full lines in Fig. II to the position shown in dotted lines in Fig. II, to disengage said blade from the cylinder 29. That turning movement, of ninety degrees, presents the flattened portion of the shaft 32 toward the detent lever 32' and thus permits the spring 32'' of said lever to uplift it from the position shown in full lines in Fig. II to the position indicated in dotted lines in Fig. II, in which its pointed right hand end 50 is engaged between adjoining teeth of the de- 55

tent gear 72 to prevent turning movement of said gear by its shaft 74.

Said shaft 32 is the pivot of the rocker frame 33 which carries the selector gear 34, so that with the blade 31' thus uplifted, clockwise, in Fig. II, said gear may be manually lifted by tilting said frame 33 counter-clockwise, and be slid axially to present said gear 34 in mesh with any two opposite gears in the two conical assemblages of gears 36 and 37, which are disposed for cooperation, to effect correct computation with reference to that selected price.

When said blade 31' is lowered to the position shown in full lines in Fig. II, and in dotted lines 15 in Fig. IV, said shaft 32 is turned so that its flattened eccentric portion pushes said lever 32' downward to the position shown in full lines in Figs. II and IV in which it is then held, by the concentric portion of said shaft, out of engagement 20 with the teeth of said detent gear 72.

As shown in Fig. III, said assemblage of gears 36 is keyed in rigid connection with the sleeve 38 which is journaled on said shaft 8, as shown in Fig. III, and is connected by a train of gearing so 25 as to be driven by the shaft 11 of the conical assemblage of gears 13, 14, which represent whole cents of the price. As indicated in Fig. II, that train includes the pinion 11' on said shaft 11, which pinion adjoins the intermediate housing 30 frame plate 39 in which the left hand end of said shaft 11 is journaled, as shown in Fig. III. Said pinion 11' is in mesh with the idle gear 40 journaled on the stationary stud 39' fixed in said frame 39. Said gear 40 is in mesh with the gear 35 41 which is rigidly connected with the sleeve 42 which is loosely journaled on the shaft 43. Said sleeve 42 has at its left hand end with reference to Fig. III, the gear 45 which is in mesh with the left hand end gear of the assemblage 36. As 40 shown in Fig. III, said shaft 11 carries the gear 10 in mesh with the gear 9 carried by the sleeve 7 which is journaled on the shaft 8. Said sleeve 7 has rigidly connected therewith the bevel gear 6 in mesh with the bevel gear 5 on the shaft 3 45 which has the cross pin 2 connecting it with the meter shaft 1 which is thus connected to rotate said assemblage 36 by the passage of liquid through the meter.

Said assemblage of gears 37 is rigidly connected with the shaft 46 which is journaled in the left hand end frame 47 and said intermediate frame 39, as shown in Fig. III. Said shaft 46 has formed thereon, adjoining said intermediate frame 39, the pinion 48, shown in Fig. III, which 55 is in mesh with the idle gear 49 which is journaled on the shaft 50 fixed in said intermediate frame 39, and said idle gear 49 engages the carrier gear 51 of the planetary gear train shown in section in Fig. III.

Said planetary gear train includes the sun gear 52, which is fixed on the left hand shaft end of the long pinion 15 and is in mesh with the pair of diametrically opposite planetary gears 53 which 65 are respectively journaled on studs 53' fixed in said carrier gear 51 at one end and in the ring 51' at the other end, as shown in Fig. III. Said planetary gears 53 are in mesh with the respective gears of a diametrically opposite pair 54, shown 70 in section in Fig. III, which are journaled on studs 54' fixed in said carrier gear 51 at their right hand ends shown in Fig. III and which are fixed at their left hand ends in the carrier ring 51'.

As shown in Fig. III, said planetary gears 54 are 75 in mesh with the second sun gear 56 which is in

coaxial relation with said long pinion 15 and first sun gear 52.

As shown in Fig. III, said sun gear 56 is rigidly connected with the shaft 56' which is journaled at its right hand end in said first sun gear 52 5 and at its left hand end in the housing end frame plate 47. As shown in Fig. II, said shaft 56' has rigidly connected therewith the pinion 57 in mesh with the idle gear 58 journaled on the stud shaft 59 fixed in said housing frame plate 47. Said idle gear 58 has in unitary relation therewith the gear 60, which is in mesh with the gear 61 shown in section in Fig. III. As shown in Fig. III, said gear 61 is carried by the sleeve 62 journaled on the shaft 63 and which is rigidly connected with the cents dial 64 shown in section in Fig. III; said dial 64 is operatively connected with the opposite counterpart dial 65 at the opposite, right hand, side of the mechanism shown in Fig. III. Said gear 61 is only frictionally engaged with said sleeve 62 by the spring 62', shown in Fig. III, to permit said cents dials 64 and 65 to be set back to zero position.

The hub 64' of said cents dial 64 is provided with double gears 70, shown in section in Fig. III. Said gears 70 are in mesh with said detent gear 72 which is rigidly connected with the shaft 74 journaled in the three housing frame plates 39, 47, and 76, the latter being shown at the right hand side of Fig. III.

Incidentally, said shaft 74 with which said detent gear 72 is rigidly connected, is employed to set the indicating dials back to zero position and, consequently, said detent lever 32' prevents the operation of such zeroizing means during the above described operation of changing the speed of the change gearing in accordance with the selected price. This is a division of my original application Serial No. 145,056 which has been restricted to said zeroizing means.

As indicated in Fig. III, said slotted cylindrical element 29 is in coaxial relation with another similar element 20 having slots 22 adapted to be selectively engaged by the blade 18 on the rocker frame 17 for selectively connecting the selector gear 16 with said conical gear assemblage 13, 14. However, such construction and arrangement is the subject matter of Letters Patent of the United States No. 2,106,686 granted January 25, 1938, to Joseph C. Woodford, as assignor to John Wood Manufacturing Company, Inc., pursuant to an application copending herewith; said corporation being the assignee of this invention.

Therefore, I do not desire to limit myself to the precise details of construction and arrangement herein set forth, as it is obvious that various modifications may be made therein without departing from the essential features of my invention, as defined in the appended claims.

I claim:

1. The combination with a driving element; of change-speed mechanism, operatively connected with said driving element, and including a detent gear, two conical assemblages of gears, with their axes parallel, the gears in each assemblage being in coaxial relation; a selector gear, adjustable axially, parallel with the axes of said gear assemblages, and transversely thereto, for selective connection with any two opposite gears in said two assemblages; locking means for said change-speed mechanism, including a spring pressed detent lever for engaging teeth of said detent gear, and thereby rendering said change-speed mechanism inoperative unless and until said selector gear is properly engaged with any selected gears of said as- 75

semblages; means for releasing said detent lever from engagement with the teeth of said detent gear, consequent upon proper engagement of said selector gear with said assemblages, including a shaft, supporting said selector gear and having a flattened eccentric portion and a concentric cylindrical portion, alternately presentable in registry with said detent lever by rotation of said shaft; said detent lever being engaged with said detent gear by its spring, when the eccentric portion of said shaft is presented to said lever, and said detent lever being displaced from engagement with said detent gear when the cylindrical portion of said shaft is presented to said detent lever; and means for manually turning said shaft, including a blade forming a handle, and a rocker frame holding said blade and axially movable on said shaft with said selector gear; and a slotted element for engaging said blade in any selected position of adjustment of said selector gear and then preventing accidental axial movement of said selector gear.

2. The combination with a driving element; of change-speed mechanism, operatively connected with said driving element, and including a detent gear, a conical assemblage of gears, in coaxial relation; a selector gear, adjustable axially, parallel with the axis of said gear assemblage, and transversely thereto, for selective connection with any gear in said assemblage; locking means for said change-speed mechanism, including a spring pressed detent lever for engaging teeth of said detent gear, and thereby rendering said change-speed mechanism inoperative unless and until said selector gear is properly engaged with any of the gears of said assemblage; means for releasing said detent lever from engagement with the teeth of said detent gear, consequent upon proper engagement of said selector gear with any gear of said assemblage, including a shaft, sup-

porting said selector gear and having an eccentric for cooperation with said detent lever by rotation of said shaft, said detent lever being engaged with said detent gear by its spring, when the least radius of said eccentric is presented to said lever, and displaced from engagement with said detent gear when the greatest radius of said eccentric is presented to said detent lever; and means for manually turning said shaft, including a rocker frame axially movable on said shaft with 10 said selector gear.

3. The combination with a driving element; of change-speed mechanism, operatively connected with said driving element, and including a detent gear, an assemblage of gears of different sizes, in 15 coaxial relation; a selector gear, adjustable axially, parallel with the axis of said gear assemblage, and transversely thereto, for selective connection with any gear in said assemblage; locking means for said change-speed mechanism, including a 20 spring pressed detent lever for engaging teeth of said detent gear, and thereby rendering said change-speed mechanism inoperative unless and until said selector gear is properly engaged with any of the gears of said assemblage; and means 25 for releasing said detent lever from engagement with the teeth of said detent gear, consequent upon proper engagement of said selector gear with any gear of said assemblage, including a 30 shaft, supporting said selector gear and having an eccentric for cooperation with said detent lever by rotation of said shaft; said detent lever being alternately engaged with said detent gear by its spring, and displaced from engagement with said 35 detent gear, by turning movement of said shaft; and means for manually turning said shaft, including a rocker frame movable on said shaft with said selector gear.

EINAR M. ORBECK. 40
